United States Patent Office

Des. 190,041
Patented Apr. 4, 1961

190,041

PLATE OR SIMILAR ARTICLE

John H. Reiser, Downey, Calif., assignor to Wallace
China Co., Ltd., Los Angeles, Calif., a corporation of California

Filed Nov. 25, 1960, Ser. No. 62,971

Term of patent 14 years

(Cl. D44—15)

The figure is a plan view of a plate of conventional configuration, showing my new design.

I claim:

The ornamental design for a plate or similar article, substantially as shown and described.
